UNITED STATES PATENT OFFICE.

LAZARD KAIIN, OF HAMILTON, OHIO, ASSIGNOR TO F. & L. KAIIN & BROS.,
OF SAME PLACE.

DESIGN FOR A GAS-STOVE.

SPECIFICATION forming part of Design No. 23,854, dated December 4, 1894.

Application filed October 29, 1894. Serial No. 527,351. Term of patent 14 years.

To all whom it may concern:

Be it known that I, LAZARD KAHN, a citizen of the United States, residing at Hamilton, Butler county, Ohio, have invented and produced a new and original Design for Gas-Stoves, of which the following is a specification, reference being had to the accompanying drawing, showing a front elevation thereof.

- 10 A vertical series of round tubes 1 bear upon their front faces escutcheon plates 2, each consisting of a central panel of substantially elliptic outline prolonged at top and bottom into narrower fanciful ornaments
- 15 and flanked by scroll-shaped ornaments 3, these scroll-shaped ornaments approaching each other so closely between neighboring escutcheons as to give to the entire group of escutcheons the characteristic of a single
- 20 large facial ornament upon the group of

tubes. The tubes rise from a base 4 of rectangular form provided at its corners with outwardly projecting claw shaped feet 5. The base 4 is surmounted by a super-base 6 somewhat smaller than the top of the base 4 so as to produce a shoulder at the juncture, the front margin of the super-base 6 having a transversely fluted central portion 7 between plain end portions. That portion of the base between the legs and nearest the floor presents a horizontal series of pierced-work panels 8. At the base of the tubes circular enlargements 9 join the super-base 6.

I claim—

The design for a gas stove as herein shown and described.

LAZARD KAIIN.
